MECHANICAL MOVEMENT

Grant Hammond, New Haven, Conn.

Application June 12, 1934, Serial No. 730,341

1 Claim. (Cl. 74—436)

My invention relates to that class of devices employed to produce intermittent movement of one mechanical element by another, and an object of my invention, among others, is to produce a device of this type in the use of which an extremely steady movement may be obtained and one in which the periods of rest of the driven member may be varied to an unlimited extent.

10 One form of a mechanical movement embodying my invention and in the construction and use of which the objects herein set out, as well as others, may be attained is illustrated in the accompanying drawing in which—

15 Figure 1 is a front view of a device embodying my invention in one of several different forms.

Figure 2 is an edge view of the same.

Figure 3 is a top view.

20 Figure 4 is a detail view illustrating the operation of the retainer.

Many forms of apparatus in use at the present time require an intermittent movement of one part with respect to another, as for instance in the operation of moving picture apparatus in which it is necessary that the film be intermittently brought to rest, such periodic movement and intervals of rest being made use of in many other different forms of apparatus. My improved mechanical movement herein illustrated and described enables the driven member to glide easily from a condition of rest to that of movement and vice versa with extreme steadiness irrespective of the rapidity

35 of movement, such device being illustrated in the drawing herein in one of several different forms, the numeral 5 denoting a base and 6 a standard rising therefrom, such standard having bearings for the driven member 7 which, in

40 the present exemplification, has a rotary movement. This driven member also includes a regulator 8 which determines the character of movement of the driven member, this regulator being preferably in the form of a disk of angular shape, that herein shown being rectangular. This regulator controls the degree of movement of the driven member between each of its periods of rest.

45 A driver 9 is secured to a driving shaft 10 which may be driven in any desired manner from any suitable source of power. This driver, in the particular form herein shown, constitutes a wheel which is keyed to the shaft 10. This driver embodies an actuator 11 in the

5 9 and a retainer 12 which constitutes the concentric periphery of the driver. The actuator or groove 11 may be of any desired length, that herein shown extending for an angle of ninety degrees on the periphery of the driver, and the retainer therefore constituting two hundred and seventy degrees of the periphery of the driver.

In order to direct the corners 13 of the regulator 8 into the actuator or groove 11 a guide 10 in the form of a cam is located at the entrance of said groove in the path of movement of the corners 13, the latter when engaging said cam being directed into the groove. In the particular form herein shown this guide comprises 15 a plate 16 attached in any suitable manner to the side of the driver 9 and having a lip 17 inturned to engage said corners and thereby rotate the regulator 8 to engage said corners in said groove.

20 From this it will be seen that when the driver is rotated the corners 13 of the regulator 8 will be entered in the actuator or groove 11 and will pass across the driver 9 and will pass out of said groove leaving the next following corner in position to enter the groove when the latter is presented to the corner in the rotation of the driver 9. When a corner 13 leaves the groove the flats 14 on the regulator will be left in contact with the retainer 12, this being the concentric portion of 25 the disk or driver 9, and the regulator will be held in this position until the groove or actuator 11 is again presented to receive the corners 13 of the regulator.

30 35 As hereinbefore stated the actuator or groove 11 and the retainer 12 may occupy such relative portions of the periphery of the driver 9 that the relative periods of rest and of movement of the regulator may be readily determined by simply changing the length of the retainer to obtain such period of rest as may be desired.

40 45 In accordance with the provisions of the patent statutes I have described the principles of operation of my invention together with the device which I now consider to represent the best embodiment thereof; but I desire to have it understood that the device shown is only illustrative and that the invention may be carried out by other means and applied to uses other than those above set out.

50 I claim:

55 A mechanical movement including a rotatably mounted driver member composed of a single piece of short cylindrical form and having a

groove extending peripherally laterally across its face, a rotatably mounted driven member of square shape having its sides resting squarely against the periphery of the driver member and having corners to enter said groove, the length of each side of said driven member being at least as great as the width of the peripheral face of said driver member, whereby a single

step movement is imparted to the driven member by the entrance and exit of a single corner into and out of said groove and a guide comprising a cam secured to the side of said driver member and with a cam lip overlying its periphery to engage the corners of said driven member and guide said corners into said groove.

GRANT HAMMOND.
